UNITED STATES PATENT OFFICE.

LAURENT GACHET, OF PARIS, FRANCE.

RAILWAY SIGNAL APPARATUS.

SPECIFICATION forming part of Letters Patent No. 698,269, dated April 22, 1902.

Application filed November 3, 1900. Serial No. 35,374. (No model.)

To all whom it may concern:

Be it known that I, LAURENT GACHET, a subject of the King of Italy, residing in Paris, France, have invented certain new and useful Improvements in Railway Signal Apparatus, of which the following is a specification.

The object of this invention is to provide means for indicating at all times to the engineer in charge of a locomotive whether the track upon which he is running is clear for some distance or whether the same is not clear and caution must be exercised to avoid a collision or danger of a collision with a train ahead traveling either in the same or opposite direction.

The object of the invention is, further, to provide means for indicating to the engineer in case the track is not open whether a train ahead is moving in the same or in opposite direction.

For these purposes the invention consists in the combination, with certain signaling devices located upon the locomotive, of a source of electricity also carried thereby, circuit-closers of certain peculiar construction located one at each side of the locomotive, and tripping mechanisms arranged adjacent the railroad-track and in the path of said circuit-closers, as will be fully described hereinafter and finally pointed out in the claims.

The invention consists, further, in certain novel features of construction of the circuit-closers and of the tripping devices, as will also be more fully described hereinafter and claimed.

In the accompanying drawings, Figure 1 is a side elevation of a portion of a railway-track and a locomotive provided with my signaling apparatus. Fig. 2 is a plan view of Fig. 1. Fig. 3 is a perspective view, drawn on a larger scale, of the tripping devices. Fig. 4 is a rear elevation, on a larger scale, of the circuit-closers. Fig. 5 shows the circuit-closers in rear elevation and illustrates in diagram the circuits of the same and the signaling devices located in the cab of the locomotive. Fig. 6 is a side view, partly in vertical section, of one of the circuit-closers, this figure indicating also in dotted lines the action of one of the tripping devices upon said circuit-closer. Figs. 7, 8, 9, and 10 indicate the positions of the various parts of the apparatus under dif-

ferent conditions of service, as will more fully appear hereinafter; and Fig. 11 is a diagram illustrating the location of the various tripping devices upon an extended length of track.

Similar characters of reference indicate corresponding parts.

In carrying out my invention the track to be covered is divided into a plurality of sections or "blocks," and at each end of each section or block is arranged a tripping device, the tripping devices of each section being connected with each other, as by a chain or other means. These tripping devices are located in the path of and are adapted to trip certain circuit-closers carried by the locomotive. These circuit-closers are composed of a plurality of fixed and swinging blades and are located at opposite sides of the locomotive.

The circuit-closer *a*, Fig. 4, which is at the right-hand side of a locomotive—in other words, upon that side of the locomotive normally at the same side of the track as that at which the tripping devices are located—comprises an inverted-U-shaped frame *b c d*, rigidly secured to the locomotive and provided with a rigid intermediate stop-blade *e*, also projecting downwardly, parallel with the downwardly-projecting fixed or rigid blades *b* and *c*. To the upper or body portion *d* of the frame is hinged at *w* a depending blade *f*, which overlaps the blade *b*, said blade *f* being permitted thereby swinging movement in one direction, but not in the other. A second swinging blade *g* is also pivoted at its upper end to the body portion of the frame and is adapted to swing in the same direction as the blade *f*, said blade *g* being limited in its opposite movement by the fixed or rigid blade *c*. Between the blades *f* and *g* is located a swinging blade *h*, which is also pivoted to the frame and adapted to swing in like direction, its movement in the opposite direction being limited by the intermediate fixed stop-blade *e*. Said blade *h* is preferably shorter than the blades *f* and *g* and is arranged adjacent the blade *f* and not between the blades *e* and *g*. Upon the opposite side of the frame is pivoted at its upper end a swinging blade *i* of approximately the same length as *h*, but located adjacent the blade *g* and not between the blades *e* and *f*. The blade *e* serves as a

stop for limiting the swinging movement of both blades *h* and *i*. Upon the opposite sides of the locomotive is arranged a second circuit-closer, constructed, like the first, of rigid and movable members. The outer blades *b*' and *c*' are fixed. Pivoted to swing at the same side of the circuit-closer as the blade *f* of the circuit-closer *a* is a swinging blade *f*', adjacent the fixed blade *b*'; also to the hinge *w*' of the body *d*' of this circuit-closer *a*' is pivoted to swing in the same direction a blade *g*'; also a shorter blade *h*', whose motion in opposite direction is limited by the fixed blade *c*'. Pivoted to swing at the opposite side of this circuit-closer *a*' is a blade *i*', corresponding to the blade *i* and limited in its swinging movement by a fixed stop-blade *e*'. Each of the blades *f* *g* *f*' *g*' is provided with a tubular contact-socket *o*, Figs. 5 and 6. By means of a suitable bracket *m* contact-pins *m*' are supported in the path of and located to enter the contact-sockets of the blades *f* and *g*. A similar bracket *p* supports in like manner contact-pins *p*' for engagement by the sockets of the blades *f*' *g*' in their swinging motion. Upon the cab is arranged a signal device *k*'—such, for example, as an electric bell. Wires 3 4 connect, respectively, the blades *g* *g*' with one binding-post *k* of said bell. Another signal device—such, for example, as a similar bell *l*'—is also located on the cab of the locomotive, and wires 5 and 6 connect the contact-sockets, respectively, of the blades *f* and *f*' with one binding-post *l* of said signal device. The two contact-pins *m*' are connected through the bracket *m* by means of a wire 7 with the negative pole of an electric battery or other suitable source of electric current 9, and the pins *p*' are similarly connected through the bracket *p* by means of a wire 8. A wire 10 connects the positive pole of the battery 9 with the binding-post *k*' of the bell *k*', and a wire 11 connects the positive pole of said battery with the binding-post *l*' of the bell *l*'. Arranged adjacent the track and in the path of either of said circuit-closers—*i. e.*, in the path of one circuit-closer when the locomotive is running in one direction and in the path of the opposite circuit-closer when the locomotive is running in the opposite direction—is a tripping mechanism composed of two connected tripping devices, one at each end of the block to be protected. The tripping device at one end of the block is composed of a shaft *q*, suitably mounted in horizontal position, and tripping-arms mounted on said shaft and arranged in two sets. The first set of arms comprises an arm *r*, rigidly connected with a sleeve *r*''', loosely mounted on said shaft, and an arm *r*', also connected rigidly with said sleeve at right angles to the arm *r*. A second set consists of arms *s* *s*', also arranged at right angles and both rigidly connected to a sleeve *s*''', loosely mounted on the spindle *q*. A cross-bar *r*'' extends rigidly to the arm *r* and extends across into the path of the arm *s*. The tri-

ping device at the opposite end of the block comprises similar arms *r* *r*', rigidly connected to a corresponding sleeve *r*''', mounted loosely upon a corresponding horizontal shaft *q*, and arms *s* *s*', also arranged at right angles and rigidly connected with the sleeve *s*''', also loosely mounted upon the same shaft *q*. A cross-bar *r*'' extends from the arm *r* into the path of the arm *s*. The two tripping devices are arranged face to face—in other words, so that when the arms *r* and *s* of both devices are vertical, as shown in Fig. 3, the arms *r*' *s*' of the opposite devices extend away from each other—in other words, in opposite direction from the shafts *q*. Suitable brackets *n* limit the movement of the sets of tripping-arms at this point, whereby the arms *r* and *s* of the other device are permitted to swing inwardly—that is, in direction toward the center of the block or toward each other—but not outwardly, and the cross-bars *r*'' are in both cases arranged so as to extend in front of the arms *s* at the inner and not at the outer sides. Connected to each sleeve *r*''' is an operating-rod *r*''', said rods preferably extending inwardly—*i. e.*, toward the center of the blocks or toward each other—and not outwardly when the parts are in position shown in Fig. 3. A chain *t* is connected with the rod *r*''', passes over a pulley *t*', and is provided at its end with a weight *t*'', said pulley being so located that this mechanism acts as means tending to return the tripping device to which it is connected into the position shown in Fig. 1 and retain the same therein. From the operating-rod *r*''' a chain *u* extends in opposite direction over pulleys *u*' and thence to the operating-rod *r*''' of the opposite tripping device, from which a chain *v* extends in opposite direction over a pulley *v*' and is provided with a weight *v*'', which serves when the chain *u* between the two devices is relaxed to actuate the device to which it is connected to swing the arms *r* and *s* of said device from vertical or tripping into horizontal or non-tripping position.

The tripping mechanism described is arranged at such portion of the track as to be normally in the path of the circuit-closer *a*. For example, when the locomotive is moving in the direction indicated by the arrow at the upper portion of Fig. 6 the circuit-closer *a* is arranged on the right-hand side of the locomotive, with the blades *f*, *g*, and *h* at the rear side and the tripping mechanism at the right-hand side of the track in the path of said circuit-closer. In such a case the opposite circuit-closer *a*' is arranged in corresponding position at the opposite side of the locomotive in such position that the blades *f*' *g*' *h*' swing in the same direction—*i. e.*, rearwardly—as the blades *f*, *g*, and *h*, said contact-closers under these circumstances presenting the appearance of Fig. 4 when looked at from the rear. Such being the general features of the construction, it remains to so arrange the fixed and swinging blades of both circuit-

closer so that when the train is moving in the normal direction, as indicated in Fig. 6, the circuit-closer a will coöperate with the tripping devices to indicate, by means of signal-bells $k' l'$, the condition of the block—i. e., whether the same is open or obstructed, and in the latter case whether the obstructing train is moving in like or contrary direction—and when the locomotive is moving in direction contrary to that shown in Fig. 6, so that the circuit-closer a' , in the path of which the tripping devices are then located, will coöperate with said tripping devices to set the same in such position as to indicate to a train entering the block that the track is not clear. For this purpose the arm s of the tripping device at the normal entering end of the block is arranged so as to be when in tripping position, as shown in Fig. 3, in the path of the blade i , the arm r in the path of the blade b , the arm r' in the path of the blade f , the arm s' in the path of the blade g . The arm s of the tripping device at the opposite end of the block is located when in tripping position in the path of the blade h and the arm r' in the path of the blade b . With regard to the circuit-closer a' , the arm r' of the tripping device normally at the outgoing end of the section or block is located in the path of the blade f' and the arm s in the path of the blade i' . In Figs. 7, 8, 9, and 10 the tripping devices at the normal ingoing and departure ends of the block are lettered, respectively, x and y . Fig. 7 illustrates the position of the parts when the tripping mechanism has been actuated by a locomotive entering the block in normal direction. The blades i and b strike the arms s and r , respectively, of the tripping device x , thereby bringing the arms r' and s' into tripping position and the arm r' of the tripping device y into tripping position, the arm r of said device being turned out of tripping position thereby, but the arm s remaining in its original position, as shown. The two blades i and b being non-yielding give no signal to the engineer through the signal devices $k' l'$. Assuming the parts to be in this position, a locomotive z' enters the block before the first locomotive has passed out of the same, as in Fig. 8. Under these circumstances the arms r' and s' of the tripping device x actuate the swinging blades f and g , swinging the same in upward direction, as indicated in Fig. 6, until the socket o of each of said swinging blades engages the corresponding contact-pin m . This closes the electric circuits through the two signal devices k' and l' , which by their operation indicate to the engineer that there is a train ahead in the same block, which entered that block in the same direction. Assuming that instead of a train entering at the rear one enters the block on the same track as the locomotive z , but in front of the same, as z' , Fig. 9, the blade f' strikes the arm r' and is thrown thereby into contact with the corresponding pin p' , thereby sounding the signal devices l' , the blade i' strikes the arm s and swings the set of arms $s' s'$ thereby, so that the arm s' is in vertical position, the swinging movements of said set being arrested by the abutment of arm s against cross-bar r^4 . The actuation of the signal l' alone indicates to the engineer that he is entering a block into which a train has entered in the opposite direction. Should a third locomotive enter the block in the same direction as the locomotive z' , the arms $r' s'$ will now trip the blades $f' g'$ of the circuit-closer a' of the incoming locomotive, thereby closing the circuits of both alarm devices in said locomotive. On the other hand, should the parts be in position shown in Fig. 3 and the locomotive z' , traveling in opposite direction to locomotive z , be the first to enter the block z' will strike the arm s , thereby swinging, by means of the cross-bar r^4 , both sets of tripping-arms, so that the arms $r' s'$ are in tripping position and actuating the set of tripping-arms $r' r'$ of the opposite tripping device x , so that the arm r' is placed in tripping position. The arm s of the adjacent set $s' s'$ remains in tripping position. The locomotive z now entering over the tripping device x , the arm r' strikes the blade f , thereby closing the circuit through the bell l' . The arm s is struck by the blade i , whereby the set of tripping-arms $s' s'$ is turned, its motion being limited by the cross-bar r^4 of the adjacent set. Thus the signal device l' is the only one actuated, and the engineer of the locomotive z is informed that a train moving in contrary direction has already entered the block. In case no train enters the block from either direction the locomotive z upon passing out over the tripping device y sets the entire tripping mechanism in its normal position by striking with its fixed blade the arm r' and with the swinging blade h the arm s . In case the locomotive z passes out of the block over the same tripping device x over which it entered the two blades f and g strike the two arms $r' s'$, thereby forcing them in backward direction and bringing the arm r of the device y again into vertical position by means of the connecting-chain connecting the two devices. For greater security the various sections may be overlapped. This is indicated in Fig. 11, in which $x' y' x'' y'' x''' y'''$ indicate, respectively, the oppositely-arranged connected tripping devices.

Having thus described my invention, I claim as new and desire to secure by Letters Patent—

1. The combination, with a railway-locomotive, of two alarm devices, a source of electricity, two circuit-closers mounted respectively in corresponding positions on opposite sides of the locomotive, each circuit-closer comprising a plurality of fixed and swinging blades, contact-pins adapted to be engaged by certain of said swinging blades, conducting-wires connecting one of said swinging blades of each circuit-closer with

one of said alarm devices and the source of electricity, and conducting-wires connecting the other of said swinging blades in circuit with the other alarm device, substantially as set forth.

2. The combination, with a railway-locomotive, of a circuit-closer consisting of a plurality of fixed and swinging blades and connected tripping devices located one at each 10 end of the block and comprising each a horizontal shaft and two sets of tripping-arms mounted rotatably on each shaft, each set comprising two arms arranged at right angles, operating-rods, one for each tripping 15 device, connected each with one of said sets of arms, a chain connecting said operating-rods, and cross-arms projecting each from an arm of one of said sets into the path of an arm of the adjacent set, substantially as set 20 forth.

3. In a railway signal apparatus, a forked circuit-closer adapted to be carried on the locomotive and provided with outer fixed blades and an intermediate fixed stop-blade, a series 25 of hinged blades, one of which is adapted to swing in one direction and the others in the opposite direction, certain of said blades being limited in movement by said stop-blade, contact devices on some of said hinged 30 blades, and contact devices on the locomotive adapted to coöperate with said contact devices of the blades, substantially as set forth.

4. In a railway signal apparatus, a forked 35 circuit-closer adapted to be carried on the locomotive and provided with a fixed depending stop-blade, hinged blades adapted to swing in one direction, a hinged blade adapted to swing in the opposite direction, contact- 40 sockets on two of said first-named swinging blades, and contact-pins on the locomotive adapted to engage said sockets, signal devices on the locomotive, a source of electricity, and conducting-wires connecting said 45 signal devices, source of electricity and said contact sockets and pins, substantially as set forth.

5. In a railway signal apparatus, the combination with a circuit-closer consisting of a 50 plurality of fixed and hinged depending blades, and contact devices on the locomotive adapted to coöperate with certain of said hinged blades, of a tripping device consisting of a horizontal spindle, two sets of tripping- 55 arms arranged rotatably thereon and composed each of two tripping-arms, the arms of each device being arranged one after the other lengthwise of the shaft in positions corresponding to the hinged and fixed blades, and 60 an operating-rod connected with one of said sets, substantially as set forth.

6. In a railway signal apparatus, the combination, with a circuit-closer consisting of a plurality of fixed and hinged depending blades and contact devices on the locomotive adapted 65 to coöperate with certain of said hinged blades, of a tripping device consisting of a horizontal spindle, two sets of tripping-arms arranged rotatably thereon and composed each of two tripping-arms, the arms of each device being 70 arranged one after the other lengthwise of the shaft, in positions corresponding to the hinged and fixed blades, an operating-rod connected with one of said sets, and a cross-arm extending from an arm of said set into 75 the path of an arm of the adjacent set, substantially as set forth.

7. In a railway signal apparatus, the combination of two oppositely-arranged tripping devices, consisting each of two sets of angularly-arranged tripping-arms, operating-rods, one for one set of each device, connected therewith, cross-arms extending from said sets at the inner side, each into the path of the adjacent set, guide-pulleys between said 85 tripping devices, a chain passing over said pulleys and connecting said operating-rods, chains connected one with each rod and extending therefrom in opposite direction to the connecting-chain, pulleys over which said 90 chains are guided, and weights on said chains, substantially as set forth.

8. In a railway signal apparatus, the combination of a forked circuit-closer adapted to be carried upon the locomotive and comprising a depending fixed stop-blade, a series of hinged blades, one of which is adapted to swing in one direction and the others in the opposite direction, certain of said blades being limited in movement by said stop-blade, 100 contact-sockets on certain of said blades, contact-pins on the locomotive, adapted to engage the contact-sockets of the blades, alarm devices on the locomotive, controlled by said circuit-closer, and two oppositely-arranged 105 connected tripping devices comprising each a horizontal spindle, two sets of tripping-arms mounted rotatably thereon, and operating-rods, one for one set of each device, connected therewith, the tripping-arms of said devices 110 being arranged at different distances from the rail in the path of said fixed and swinging blades and adapted to coöperate with the same, substantially as set forth.

In testimony whereof I have signed my 115 name to this specification in the presence of two subscribing witnesses.

LAURENT GACHET.
